UNITED STATES PATENT OFFICE

2,288,365

WALL FORM SUPPORT

Raymond J. Moths, Shorewood, Wis.

Application July 12, 1940, Serial No. 345,047

1 Claim. (Cl. 25—131)

This invention relates to concrete construction or the like, and more particularly to concrete wall forms.

In constructing concrete walls it has been customary to tie the two sides of the wall together with either rods or wires in order to prevent the pressure of the wet concrete from bulging the walls. In such construction it is necessary either to pull out the rods and refill the holes or to clip off the wires. In either case considerable work is entailed in finishing the wall, and the finished wall is more or less susceptible to seepage of water.

One object of the invention is to eliminate tie wires or rods through concrete walls.

Another object is to form a concrete wall which will be more nearly waterproof.

A further object is to reduce the cost of concrete walls.

A further object of the invention is to simplify the construction of concrete walls and partitions.

A further object is to decrease the time required to set concrete forms.

A further object is to provide a form support that will be strong and rigid.

Other objects will become apparent from the following description.

The single drawing is a cross-section through a wall of uniform thickness showing the improved form-support in place thereon.

Referring to the drawing, the foundation 10 is poured and allowed to harden with a substantially U-shaped truss-support embedded therein. The support may comprise a pair of vertical legs 12—12, connected together at their lower ends by a horizontal spacer bar 13. Fish plates 14—14 may be integrally formed between the legs 12—12 and the bar 13 to stiffen the truss-support and prevent cracking of the foundation 10. The legs 12—12 are of such diameter as to fit within the tubular ends 15—15 of two trusses, generally designated 16—16, while the bar 13 may be a continuation of the material of the leg and be of sufficient length to give the desired spacing to the trusses and the resultant wall.

As shown on the drawing, the trusses 16—16 may be expandable and of the type covered by applicant's United States Patent No. 2,177,043, issued October 24, 1939, and applicant's co-pending application Serial No. 397,271, filed June 9, 1941.

The upper ends of the trusses are held together by a truss-support which may comprise a pair of substantially vertical pins 20—20 which are receivable within the upper tubular ends 21 of the trusses 15—15, and an adjustable spacer bar. The spacer bar comprises tubular end pieces 22—22 each of which has one of the pins 20 joined to the outer end thereof.

The interiors of the tubular end pieces 22—22 are threaded to receive a threaded bar 24 in such a manner that rotation of the bar 24 in one direction decreases the spacing of the pins 20—20 while rotation of the bar in the opposite direction increases the spacing of the pins. A nut 25 is formed integrally on the bar 24 to enable it to be turned readily.

The wall forms 30—30 may thus be built on 2 x 4's, 31—31, which are connected to the trusses 15 by nailing through brackets 32 on the trusses.

By adjusting the truss-supports properly a wall may be built either of uniform thickness or of uniformly varying thicknesses. The elimination of tie rods or tie wires not only lessens the work of finishing the wall, and gives a substantially waterproof structure, but permits the use of large sections of plywood in the construction of the forms, thus effecting further savings.

Having thus described the invention it will be realized that it is susceptible to various changes and modifications and that the type of trusses and corresponding truss-supports used may be varied to suit particular conditions, and it is not therefore, desired to limit the invention to the precise form herein shown and described, but only by the scope of the appended claim.

The invention hereinbefore described is claimed as follows:

1. In a form support for use with a concrete construction having a base, a U-shaped member adapted to be embedded in said base with the ends thereof projecting out of the base and extending parallel to the sides of the form, a pair of trusses, each truss including a tubular chord, one end of each of said tubular chords being engaged over an end of the U-shaped member to support that end of each truss, and a second U-shaped member having parallel pins engaged in the opposite ends of said tubular chords to support that end of each truss.

RAYMOND J. MOTHS.
